MULTIPLE CONTACT SELECTOR SWITCH

Joseph H. Todd, East Chicago, Ind.

Application August 6, 1934, Serial No. 738,715

2 Claims. (CL. 290—4)

The invention relates to electrical switches and has for its general object the provision of a novel switch which is capable of employment for a wide variety of purposes, for instance in analyzing 5 radio sets, testing tubes, measuring the voltage, current or resistance characteristics from the tube socket, for indicating the voltage values from point to point, resistance values from point to point, for enabling one telephone or telegraph instrument to serve a number of lines, and other 10 purposes.

An important object of the invention is to provide a switch which will be very compact and which is yet provided with means for maintaining 15 a number of local circuits while permitting an additional circuit to be controlled at will, it being a feature that the switch embodies means for enabling a certain predetermined series circuit to be maintained under certain circumstances.

Another object of the invention is to provide a 20 device of this character embodying means which will normally maintain a circuit and embodying other means which is operable to establish or discontinue a series connection with an adjunctive 25 element or circuit.

An additional object is to provide a switch of 30 this character which will be simple to make, easy to assemble and adjust, positive in action, efficient and durable in service, and a general improvement in the art.

To the attainment of the foregoing and other 35 objects and advantages, the invention preferably consists in the details of construction and the arrangement and combination of parts to be hereinafter more fully described and claimed, and illustrated in the accompanying drawings in which:

Figure 1 is a horizontal cross sectional view taken through the switch,

Figure 2 is a vertical cross sectional view,

Figure 3 is a detail vertical cross sectional view taken on the line 3—3 of Figure 1,

Figure 4 is a detail perspective view of one of the contact plates of the stator,

Figure 5 is a perspective view showing a pair 45 of the plates carried by the rotor,

Figure 6 is a top plan view showing the rotor and the calibrations associated therewith,

Figure 7 is a fragmentary bottom plan view.

Referring more particularly to the drawings, I 50 have shown my switch as comprising a stator including upper and lower disks 10 and 11 of insulating material held apart in spaced relation by bolts 12 passing through sleeves 13. These bolts 12 may be prolonged beyond either of the upper 55 or lower disks, or both, for mounting purposes.

By prolonging the bolts 12 upwardly as shown in Figure 2 it is clear that they might be associated with a panel or the like indicated by the dot and dash lines 14 in Figure 2.

Secured upon the underface of the disk 10 is a 5 series of contacts 15 formed as segmental plates shown in detail in Figure 4 and having terminal lugs 16 for attachment of conductors thereto. Secured upon the top of the lower disk 11 and arranged in circular series are similar contact 10 plates 17 having terminal lugs 18 for attachment of wires thereto.

Journaled axially through the disks 10 and 11 is a sleeve or tubular shaft 19 carrying a rotor 20 formed as a disk of insulating material which 15 is secured with respect to the sleeve or hollow shaft by nuts 21 threaded onto the shaft and engaging against opposite sides of the disk. Above the disk 10 the shaft or sleeve 19 is provided with a turning knob 22 secured as by a grub screw 23 20 and here represented as carrying a pointer 24 movable over and cooperating with an appropriately calibrated dial 25 which may be mounted in any desired manner upon the panel 14. Extending axially through the hollow shaft or sleeve 25 19 and slidable therein is a push rod 26 of insulating material provided at its lower end with an enlarged head 27 for a purpose to be described.

Secured upon opposite sides of the rotary disk 20 as by means of rivets 28 or the like are pairs 30 of contacts 29 which may have pressed-out portions 30 cooperating with the contacts 15 and 17 for the purpose of maintaining the local circuits connected to the contacts 15 and 17. Likewise secured upon opposite sides of the rotary disk are 35 contacts 31 and 32 formed with stamped-out portions 33 and 34 and adapted to cooperate with any selected pair of contacts 15 and 17. On the underside of the rotary disk 20 is a contact ring 40 35 connected with the contact 31 as by a rivet 36, and likewise secured on the underside of the rotary disk is a ring 37 which connects with the contact 32 as clearly shown in Figure 2.

Secured upon the top of the bottom disk 11 45 is a contact 38 having a pressed-out portion 39 bearing against the ring 37. The contact 38 is mounted as by means of rivets 40 and 41 which pass through the contact 38, through the disk 11 and through a metallic member 42 having 50 a terminal lug 43 for attachment of a wire thereto. The lower end of the rivet 41 is enlarged to form a contact 44. Secured upon the top of the disk 11 is another spring contact 45 having a pressed-out portion 46 bearing against the 55 ring 37. Mounted on the underside of the sta-

tionary disk 11 is an elongated spring contact 47 secured in place as by bolts 48 or the like, one of which passes through the contact 45 for establishing an electrical connection between the contacts 45 and 47. The contact 47 has one end 49 formed as or with a terminal lug adapted for connection of a wire thereto. As mentioned, the contact 47 is elongated and extends beneath and in engagement with the head 27 at the lower end 10 of the push rod 26 and has a terminal contact 50 normally engaging against the contact 44 of the rivet 41.

While it is not essential I have shown, particularly in Figure 3, ledges or ridges 51 and 52 15 on the confronting faces of the stationary disks 10 and 11 for engagement by the contacts 29 and 31 and 32 for the purpose of limiting separating movement of these contacts so that the action will be smoother.

20 In the use of the device, it will be seen that any desired local circuits may be connected with the contacts 15 and 17 and will be maintained owing to the engagement of the contacts 29 therewith which are in turn electrically connected 25 by the rivets 28. Other connections in any desired circuit, depending upon the work to be done, are to be made at the points 43 and 49. When the knob 22 is rotated so as to turn the disk 20 the contacts 31 and 32 may be brought into 30 engagement with any selected pair of the contacts 15 and 17. Under normal conditions, that is to say when the contact 50 on the elongated spring member 47 is in engagement with the contact 44, nothing happens as whatever circuit is 35 connected with the points 49 and 50 will be bridged by the contact 47. However, when the operator depresses the push rod 26 the head 27 thereon engaging against the elongated spring contact 47 will move the latter downwardly and 40 break the contact between the points 44 and 50. When this is done, it will be seen that in whatever circuit is connected with the points 43 and 49 current will flow through the member 47, rivet 48, contact 45, contact ring 37, contact 32, whichever one of the plates 17 is engaged thereby, 45 through the local circuit, back to the plate 15, contact 31, rivet 36, ring 35, contact 38, rivets 40 and 41, and contact plate 42. In this way it will be seen that whatever is to be tested or 50 whatever circuit is to be handled can be very simply thrown into series with any selected pair of the contacts 15 and 17 by the very simple expedient of depressing the push rod. When the push rod is permitted to return to its upper or 55 normal position the spring contact 47 will return to its upper position in engagement with the contact 44, thus cutting out whatever circuit is connected to the points 43 and 49 and permitting restoration of the direct connection between 60 the contacts 15 and 17.

The device is of course capable of employment for a multiplicity of purposes which are in fact so numerous that it is not believed necessary to point out in detail what they may be, especially as possibilities have been mentioned in the preliminary part of the specification. It will be seen that the switch is extremely simple and will therefore be inexpensive to manufacture and easy to use. It is thought from the above that the construction, operation and advantages will be readily apparent to one skilled in the art without further explanation.

While I have shown and described the preferred embodiment of the invention, it should be

understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. A selector switch comprising a pair of spaced stationary members provided on their confronting faces with circular series of contact plates having lugs for connection to the conductors of circuits to be tested, a rotary disk disposed between said stationary members and provided with means for imparting angular or turning movement to the same, a plurality of contacts mounted on each face of said disk and equal in number to the contacts on said members, those on one face of the disk engaging the contacts of one member and those on the other face of the disk engaging the contacts of the other member, concentric rings carried on one face of said disk, one of the disk-carried contacts being electrically connected with one of said rings and the corresponding contact on the opposite face of said disk being electrically connected with the other of said rings, all of the remaining contacts on said disk being electrically interconnected in pairs of which the two contacts of any pair are on opposite faces of the disk, contacts carried by one of the members and slidably bearing one on each of said rings, and a short circuited switch bridging the last said contact and normally held in closed position but provided with means by which it may be manually retained in open position.

2. A selector switch comprising a pair of spaced stationary members provided on their confronting faces with circular series of contact plates having lugs for connection to the conductors of circuits to be tested, a rotary disk disposed between said stationary members and provided with means for imparting angular or turning movement to the same, a plurality of contacts mounted on each face of said disk and equal in number to the contacts on said members, those on one face of the disk engaging the contacts of one member and those on the other face of the disk engaging the contacts of the other member, concentric rings carried on one face of said disk, one of the disk-carried contacts being electrically connected with one of said rings and the corresponding contact on the opposite face of said disk being electrically connected with the other of said rings, all of the remaining contacts on said disk being electrically interconnected in pairs of which the two contacts of any pair are on opposite faces of the disk, contacts carried by one of the members and slidably bearing one on each of said rings, and a short circuited switch bridging the last said contact and normally held in closed position but provided with means by which it may be manually retained in open position, the disk actuating means comprising a tubular shaft journaled in said members and carrying said disk and the short circuited switch consisting of fixed and movable members of which the latter is disposed in spanning relation to the shaft and consists of a leaf spring, the tubular shaft being provided with an axially movable push rod bearing on said leaf spring with its remote terminal projecting beyond the opposite end of the tubular shaft.

JOSEPH H. TODD.
